F. THIRY, OF HUY, BELGIUM, ASSIGNOR TO WARNER MILLER, OF HERKIMER, NEW YORK.

Letters Patent No. 72,564, dated December 24, 1867.

IMPROVED APPARATUS FOR CONTROLLING THE MOTION OF TRAVELLING-WEBS IN PAPER-MACHINES, &c.

The Schedule referred to in these Letters Patent and making part of the same.

TO ALL WHOM IT MAY CONCERN:

Be it known that I, F. THIRY, of Huy, in the Kingdom of Belgium, have invented a new and improved Apparatus for Paper-Making Machines and other Machines having Travelling-Webs and Fabrics; and I do hereby declare that the following is a full, clear, and exact description thereof, which will enable others skilled in the art to make and use the same, reference being had to the accompanying drawings, forming part of this specification.

The object of this invention is to restore the endless cloth or wire, on which the pulp or paper travels, (in the manufacture of paper, and the webs or fabrics in other manufactures,) to its true course, when, from any cause, it has a tendency to depart therefrom; and to this end I use a self-acting guiding-apparatus, as herein-after fully shown and described. In the accompanying sheet of drawings—

Figure 1 is a side view of my invention.

Figure 2 a plan or top view of the same, and

Figure 3 an end view of the same.

Similar letters of reference indicate corresponding parts.

In the manufacture of paper, the endless cloth or wire on which the pulp or paper is supported during its progress through the machine, passes over a guide-roller. This cloth is liable to displacement during the working of the machine moving either to the one side or the other out of its proper path, unless means be used to retain it in or restore it to its proper position.

By my within-described invention the cloth or web may be guided in a true position, or immediately restored to such position, whenever it departs therefrom.

The conducting-roller A, shown in red in all the figures of the drawing, is supported at one end of the movable bearing B, its other end resting in a fixed bearing. The web or cloth C, shown in blue in figs. 1 and 2, passes over this roller, forming a broken line, and giving a rotary motion to a roller. D, shown in red, is a wooden rule, which is supported at one end by a lever, E, and at the other end by a lever, E', (see more particularly fig. 2.) On this rule D there are fitted two metal blades or plates F, (I prefer copper.) Between these plates F the web or cloth passes, as shown at fig. 2. A small crank, G, on one of the journals of roller A, fig. 2, serves to impart motion to the lever H, which carries a forked lever, I, (figs. 1, 2, and 3.) J is a wheel, (see more particularly fig. 2,) which is toothed on both its faces, so that the forked lever I may catch therein, as required. Under these arrangements the web or endless cloth cannot displace itself without carrying with it the rule D, which, by the aid of the double-branched lever E, fig. 2, causes the forked or curved lever I to catch in the wheel J on one of its faces. K is a screw, having a left-hand thread, and on which the wheel J is keyed or otherwise secured, and it will be observed that on the combined motion of the rule-levers E, I, and J, the screw receives a rotary motion, and thus throws the guiding-cylinder or roller A out of square to the right or left, in the direction of the displacement of the web or cloth, and this change of position in the cylinder prevents further displacement of the web or cloth.

It should be particularly observed that the conducting-roller displaces as it were itself, the displacement being caused by the self-action of the apparatus previously described; and it should also be remarked that the conducting-roller can only displace itself in equal ratio with the displacement of the web or cloth, as the forked or curved lever I does not follow the rectilineal movement of the apparatus when working, being restrained by the lever E, which only receives motion on any displacement of the web, and from the web itself. The apparatus releases itself, the lever I being disengaged from the toothed wheel J, by the displacement of the conducting-roller A, this being essential to success; otherwise the apparatus would continue to act, and cause continual displacement of the web or cloth.

The two hooks, I, (see fig. 1,) serve to restrain the apparatus at either end of its course, as one or the other of them meets with the head of the bearer M, (figs. 1 and 2,) which arrests it, and thus prevents the lever I giving motion to the screw K.

Having thus described my invention, I claim as new, and desire to secure by Letters Patent—

The rule D, provided with the plates F, and connected to the levers E E', in connection with the screw K, double-toothed wheel J, curved lever I, lever H, and crank G, on one of the journals of the conducting-roller A, all arranged to operate in the manner substantially as and for the purpose herein set forth.

The above specification of my invention signed by me, this 1st day of December, 1866.

F. THIRY.
